UNITED STATES PATENT OFFICE.

CARL E. ANDERSON, OF GRAND HAVEN, MICHIGAN, ASSIGNOR TO BOLLING MANUFACTURING COMPANY, OF GRAND HAVEN, MICHIGAN, A CORPORATION OF MICHIGAN.

PROCESS OF FORMING A CLEVIS.

Application filed November 29, 1920. Serial No. 426,950.

To all whom it may concern:

Be it known that I, CARL E. ANDERSON, a subject of King Gustaf V of Sweden, residing at Grand Haven, in the county of Ottawa 5 and State of Michigan, have invented certain new and useful Improvements in a Process of Forming a Clevis, of which the following is a specification.

This invention relates to an improved 10 article of manufacture and to an improved process of forming the same. The principal object of the invention is to provide an improved form of clevis or similar article and to furnish an improved method of 15 stamping and pressing the article from a single sheet of metal. Devices of this kind have heretofore been forged or formed of wrought iron, with the result that the cost of manufacture has been very great and sufficient strength could not be obtained in 20 articles of small size.

The various objects and advantages of the invention will appear more clearly from the following specification taken in connection 25 with the accompanying drawings in which one embodiment is illustrated.

In the drawings—

Figure 1 shows a top plan view of the sheet metal blank which is formed as the 30 first step in the process of manufacture;

Fig. 2 shows a side elevation of the sheet metal blank after the central part thereof has been depressed;

Fig. 3 shows a top plan view of the blank 35 at the end of the next succeeding stage of the process after the lateral edges of the central part have been trimmed off;

Fig. 4 shows a longitudinal section through the blank, illustrating the fourth stage of 40 the process which consists in contracting and increasing the depth of the central depression until it assumes substantially the form of a cylinder;

Fig. 5 shows a top plan view of the blank, 45 illustrating the method of holding it during the fourth stage of the process;

Fig. 6 shows a longitudinal section through the blank, illustrating the form of the article after the fifth stage of the process;

Fig. 7 shows a top plan view of the arti-

cle at the end of the sixth stage of the process;

Fig. 8 shows a longitudinal section through the completed clevis formed by bending the arms of the article, as illustrated in Fig. 7; 55

Fig. 9 shows a side elevation of the completed clevis after the cylindrical portion thereof has been threaded.

The article is formed from a blank 10 of 60 cold sheet steel or the like of uniform thickness, the blank consisting of a circular central portion 10^a and two oppositely directed rectangular arms 10^b. After the blank has been formed, it is operated upon by a punch and die to force the central part downwardly and form a cup-shaped portion 11, as illustrated in Fig. 2. The next step of the process consists in shearing off the lateral edges of the enlarged central portion, 70 these parts being cut away as shown in Fig. 3 to remove the portions 12, thus giving the central part a lateral contour 13 which can be securely gripped during the succeeding operations. The article having the form shown 75 in Fig. 3 is then placed between two clamping members 14, as shown in Fig. 5, these members having irregular surfaces adapted to fit the irregular surfaces 13 on the opposite sides of the blank. The central cup-shaped part is then reduced in diameter and increased in depth, as illustrated by the dotted lines 15 in Fig. 4, until it assumes a substantially cylindrical shape. The next

stage of the operation consists in flattening 80 the end of the central cylindrical portion and punching the ends of the arms 10^a to form two bosses or projections 17. An aperture 18 is then formed through the circular end of the central cylinder 19 and apertures 20 are punched through the bosses 17, as shown in Fig. 6. After these operations have been completed, the outer edges of the lateral arms 10^a are trimmed off to remove 85 the portions illustrated by dotted lines 21 in Fig. 7, thus giving smooth curved lateral edges to each of the projecting arms of the article. The final stage of the process consists in bending the arms 10^a until they lie

parallel to each other and parallel to the 90 100

axis of the cylinder 19, as shown in Fig. 8. The article may be used in the form shown in Fig. 8 or the cylinder 19 may be internally threaded as shown at 22 in Fig. 9 to enable it to be readily attached to a rod or the like.

The clevis formed by this process has great strength and is capable of being rapidly formed at a very small cost. The invention is particularly adapted for the formation of small clevises and connecting members, such as those which are used on the brake rods of automobiles for example.

The formation of the bosses 17 is adapted to increase the wearing surface on the side of the clevis.

Although I have illustrated one form of article to be formed by this process and have described certain steps of the process as being performed in a certain order, it will be understood that various changes may be made in the article and in the process of forming the same without departing from the scope of the appended claims.

26 I claim:

1. The process of forming a clevis, which comprises cutting a sheet-metal blank having oppositely projecting arms, forming a cylindrical depression in the central part thereof between said arms, forming bosses on the opposite ends of said arms, and bending said arms into parallel relation.

2. The process of forming a clevis, which comprises the operations of taking a sheet-metal blank having two oppositely projecting arms forming a cylindrical depression in the central part of said blank between said arms, forming apertures through the end of said depression and through the ends of said arms, and bending said arms into parallel relation.

3. The process of forming a clevis which comprises cutting a sheet-metal blank having a circular central portion with oppositely projecting arms, forming a depression in said central portion, bending said arms into positions parallel with each other, and forming an aperture through the bottom of said depression.

50 4. The process of forming a clevis, which consists in forming a sheet-metal blank having an enlarged central portion and oppositely projecting arms, forming a cylindrical depression in said central portion, trimming off the metal from opposite sides of said central portion, and bending said arms into parallel relation.

55 5. The process of forming an article of manufacture, which consists in forming a sheet-metal blank having an enlarged central portion and oppositely projecting arms, forming a depression in said central portion, trimming off the metal on opposite sides of said central portion to form sur-

faces of irregular contour conforming to the curvature of said depression, and further drawing the metal of said depression to impart a cylindrical contour to its walls.

60 6. The process of forming an article of manufacture, which consists in forming a sheet-metal blank having an enlarged central portion and oppositely projecting arms, forming a depression in said central portion, trimming off the metal on opposite sides of said central portion to form surfaces of irregular contour conforming to the curvature of said depression, further drawing the metal of said depression to impart a cylindrical contour to its walls, and forming bosses on the ends of said arms.

65 7. The process of forming an article of manufacture, which consists in forming a sheet-metal blank having an enlarged central portion and oppositely projecting arms, forming a depression in said central portion, trimming off the metal on opposite sides of said central portion to form surfaces of irregular contour conforming to the curvature of said depression, further drawing the metal of said depression to impart a cylindrical contour to its walls, forming bosses on the ends of said arms, and bending said arms into a position parallel to the axis of said cylindrical depression.

80 8. The process of forming an article of manufacture, which comprises the operations of punching a sheet-metal blank to form a depression in the central part thereof, drawing the walls of said depression into substantially cylindrical form, forming bosses on the ends of said blank on opposite sides of said depression, and bending the arms of said blank on opposite sides of said depression into positions substantially parallel with the axis of said depression.

85 9. The process of forming an article of manufacture, which comprises the operations of forming a sheet-metal blank having a central portion and oppositely projecting arms, forming a depression in said central portion, drawing the walls of said depression to impart a substantially cylindrical contour thereto, trimming the metal from opposite sides of said depression to

90 impart an irregular contour to the lateral edges of the blank, forming bosses near the ends of said arms, punching apertures through said bosses and through the end wall of said depression, trimming the metal from the lateral edges of said arms, and bending said arms into positions substantially parallel with the longitudinal axis of said cylindrical depression.

95 10. The process of forming a clevis from a sheet-metal blank having an enlarged central portion and two oppositely projecting arms, which comprises the operation of forming an aperture through said central

portion and through the ends of said arms, and bending said arms into parallel relation.

11. The process of forming a clevis from a sheet-metal blank having an enlarged central portion and two oppositely projecting arms, which comprises the operations of forming a cylindrical projection on said cen-

tral portion, forming an aperture through said projection, forming apertures through the end portions of said arms, and bending 10 said arms into parallel relation.

In testimony whereof, I have subscribed my name.

CARL E. ANDERSON.
